UREA COATED STIFFENING SHEET

John Harold Gaquin, Haverhill, and Ronald W. Morse, Newton, Mass., assignors to Beckwith-Arden Inc., Dover, N.H., a corporation of New Hampshire
Filed Sept. 17, 1959, Ser. No. 840,667
1 Claim. (Cl. 154—46)

This invention comprises a new and improved sheet material for stiffening parts of shoes and which, although coated or impregnated with a partially condensed and normally tacky urea compound, is, in fact, non-tacky in handling, storage and shipment and until ready for actual assembly in a shoe upper.

Sheet material carrying such urea compounds have been used successfully heretofore in stiffening box toes and counters but the material has been subject to the very serious fault that in warm and humid weather it will turn tacky, making it inconvenient and unpleasant to handle and difficult to separate when packaged in stacked formation.

The present invention solves this long-standing problem and makes available a stiffening material that has also other unexpected advantages. In one aspect the invention consists in covering or laminating upon the urea-carrying surfaces of the base sheet a porous, absorbent tissue or membrane. This is applied so that it blends and merges with the sheet material and its effect is completely to mask all trace of tackiness which would otherwise be due to the presence of the urea compound. If the sheet material is coated on one surface only with the urea compound, it is necessary to cover only that surface of the material with the tissue. If the material is impregnated or coated on both surfaces, the tissue is applied to both surfaces thereof.

The material in that form may be handled as so much dry fabric having appreciably no tackiness and no tendency to block when packaged in the form of stacked blanks.

The urea component of the material of our invention is caused to undergo condensation or polymerization to a final hard insoluble-infusible stage by the action of a catalyst. Resins of this type are well-known in the art and one which is suitable for purposes of this invention is a water-soluble A-stage urea formaldehyde resin, such as Urac 180 sold by American Cyanamid Company, and which may be catalyzed effectively with a solution of ammonium chloride. It has been found that the presence of the porous tissue lamination of our improved stiffening material has the important advantage of retaining the liquid catalyst upon and in the most effective position for activating the urea compound and causing its final polymerization to take place. That is to say, the tissue being porous and absorbent tends to prevent the liquid catalyst from running off the impregnated base sheet and instead holds the catalyst evenly distributed against the incured resin, thus promoting a much more evenly cured piece of stiffened material.

These and other features and characteristics of the invention will be best understood and appreciated from the following disclosure of a preferred manner of preparing the sheet material as shown in the accompanying drawings in which,

FIG. 1 is a diagrammatic view suggesting the steps of preparing sheet material with a single coated surface.

FIG. 2 is a similar view suggesting the steps of preparing sheet material impregnated or coated on both surfaces.

FIG. 3 is a plan view of a box toe blank embodying the invention.

FIG. 4 is a view in cross section on an enlarged scale showing the component parts of the blank of FIG. 3.

The base sheet fabric employed may be double or single napped flannel, burlap, felt, or the like and in FIG.

2

1 this is shown as being drawn from a coil 10. From this it is led over an applying roll 11 partially immersed in a bath of partially condensed urea formaldehyde solution which is effective to coat the lower surface of the sheet. The coated sheet then passes to a dryer 12 wherein the liquid coating is partially dried so that the fabric issues from the heater in a slightly tacky condition. It then passes between squeeze rolls 14 and at this point a web of tissue is drawn from a coil 13 and combined with the still tacky sheet. From the squeeze rolls 14 the laminated sheet is wound into the coil 15. The tissue drawn from the coil 13 as already stated is porous, soft and absorbent so that when pressed against the tacky surface of the base sheet it merges and blends into it with permanent adhesion.

Substantially the same process is illustrated in FIG. 2 except that in this case the sheet material drawn from the coil 10 is completely immersed in a bath 16 of urea solution so it emerges with both surfaces coated. From the bath 16 the coated material passes through the heater 12 wherein both surfaces are partially dried to a condition of tackiness. The sheet is then passed between squeeze rolls 14 and at this point tissue drawn from the coil 13 is applied to the lower surface of the sheet while similar tissue is drawn from the overhead coil 17 and applied to the upper surface of the sheet. Finally the laminated material is wound in a coil 18.

The sheet material thus prepared may now be cut into blanks for use in stiffening box toes or counters. A box toe blank as shown in FIG. 3 wherein the base textile fabric 20 is shown has united to a coextensive ply 21 of tissue, the latter being shown as partially separated from the base fabric. The blank, thus prepared, may be shipped and handled as conveniently as a piece of lightly-sized fabric. When ready for actual use it may be brushed or dipped in an ammonium solution and this is distributed over the entire surface of the blank and retained in and by the porous and absorbent tissue ply 21 in the most favorable position for causing rapid final polymerization of the urea compound and hardening of the blank in the shape which has been imparted to it by the enclosed last.

While we have referred to urea formaldehyde as a satisfactory and desirable stiffening compound, it could be within the scope of the invention to employ any other urea solution or compound having similar characteristics, such as thiourea-aldehyde, melamine-aldehyde or phenol-aldehyde.

Ammonium phosphate, phosphoric acid, hydrochloric acid or their equivalents may also be employed as the catalyst component if desired.

Suitable tissues for purposes of this invention are readily available in the open market and may be described as thin, light weight and translucent as well as porous and absorbent in texture, more absorbent than the base fabric. The tissue may be of paper stock, or cotton fabric or other cellulose sheet material of medium weight or lighter.

Where thin tissue is used it has a tendency to blend and merge with the base sheet so completely as to become substantially invisible and under such condition it is difficult for the user to determine which side of the blank should be located in contact with the shoe lining. To obviate this difficulty we employ a tissue differently colored from the underlying base sheet to indicate the urea-carrying surface of the blank.

As a further important embodiment of our invention we employ a base sheet impregnated with a thermoplastic stiffening compound. In this instance the sheet material drawn from the coil 10, instead of being untreated cotton, for example, may carry such thermoplastic component as cellulose acetate or nitrate, ethyl cellulose, methacrylate,

vinyl acetate, butyral or chloride or combinations of the same with natural gums or waxes. In using material of this kind the blank is activated by the application of the liquid catalyst, placed in the shoe upper and molded under heat and pressure while the urea component is converted by condensation to its hard insoluble stage. The action of the urea compound is to supplement the more brittle stiffening of the thermoplastic component and obviate the formation of cracks in the finished toe box or counter, providing a box toe in the shoe superior in respect to 10 life and texture to those heretofore known.

Having thus disclosed our invention and described in detail illustrative embodiments thereof, we claim as new and desire to secure by Letters Patent:

Sheet material for stiffening parts of shoes, comprising a base sheet coated on at least one surface with a partially condensed urea resin, impregnated with a dry thermoplastic stiffening compound, and having a covering 5 ply of absorbing cellulose tissue adhered to its urea coated surface and thus rendered non-tacky.
